LAMP

George Sperti, Covington, Ky., assignor to Sperti
Lamp Corporation, New York, N. Y., a corpo-
ration of Delaware

Application January 25, 1932, Serial No. 588,749

6 Claims. (Cl. 176—1)

This invention relates to lamps of the type combining a source of visible radiation such as an incandescent filament with an arc constituting a source of visible and ultra-violet radiation and particularly to an arc element for use in such or other lamps or for use as an arc lamp alone.

In prior applications of George Sperti, for example, application Serial No. 572,394, filed October 31, 1931, there are disclosed lamps of the above type wherein the source of visible radiation is constituted by an incandescent filament of tungsten or the like and wherein the arc is established between electrodes in an atmosphere of ionized gas or vapor such as mercury. The resultant spectrum of such a lamp is that of the incandescent filament having superimposed thereon the spectrum of the arc, so that the radiation from the lamp closely resembles natural sunlight in character and quality. The arc radiation reinforces the radiation from the incandescent filament particularly in the short ultra-violet which is of recognized therapeutic value, and means are provided for preventing the emission from the lamp of objectionable radiations shorter than about 2800 to 2900 Angstrom units.

Lamps of this type are designed for general illumination so as to provide artificial light equivalent or nearly equivalent to natural sunlight and to this end they should be capable of use in place of the ordinary incandescent lamp at normal lighting voltages and currents. The lamp described in the aforesaid application embodies both an outer and an inner bulb, the incandescent filament being disposed in the outer bulb and the arc in the inner bulb so that these two sources may be operated independently as regards conditions such as gas and vapor pressure, etc. Hence the arc element is complete in itself and may, if desired, be used without the incandescent filament as an arc lamp. The design of the lamp described above, however, is such that it may be used to replace the ordinary incandescent lamp for all purposes without the use of external controlling and starting devices, ballasts, etc. The lamp disclosed in the aforesaid application is particularly adapted for use with alternating currents, although also operable with direct current, and the object of the present invention is to provide a novel lamp of the type described and more particularly a novel arc element for use alone or in such a lamp which is particularly adapted for use with direct current, although it may also be used with alternating current.

One embodiment of the invention has been

illustrated in the accompanying drawing, but it is to be expressly understood that said drawing is for purposes of illustration only and is not to be construed as a definition of the limits of the invention, reference being had to the appended claims for this purpose.

In the drawing,

Fig. 1 is a perspective view of a lamp embodying the invention; and

Fig. 2 is a sectional view of a part of the lamp 10 shown in Fig. 1.

Referring now to the drawing, the lamp in the form shown comprises a bulb 1 of any desired type, size and shape which is mounted in the usual or any suitable base 2. In the form shown, the bulb 1 is constituted of material which transmits ultra-violet light of the desired wave lengths, that is, ultra-violet radiations longer than 2800 to 2900 Angstrom units. The bulb may, if desired, be of material which is opaque to shorter radiations, but in the form shown it is unnecessary that this bulb have filtering characteristics. Sealed in the neck of the bulb is a stem or standard 3 constituting the usual means for introducing conductors 4 and 5 into the bulb 25 and for supporting the various elements within the bulb. An incandescent filament 6, of tungsten or other suitable material, is supported in the bulb 1 by means of wires 7 and 8 that are fused in the stem 3, the wire 7 constituting a 30 connection from one end of the filament to the conductor 4. Filament 6 may also be supported by a plurality of wires 9 carried by a bead 10 formed on an inner bulb 11 which is in turn supported from the stem 3 by means of a supporting band 12 and supports 13 and 14. In most cases, it is desirable that the bulb 11 have filtering characteristics, that is, the bulb should transmit the desired radiations but be opaque or substantially opaque to the undesired radiations 40 from the arc. It will be understood that the construction thus far described constitutes no part per se of the present invention but is shown merely to illustrate the application of the invention to a practical form of lamp.

The inner bulb 11 is sealed by means of a stem or standard 15 and preferably contains a quantity of mercury or other ionizable gas or vapor which produces the desired radiations. Enclosed within the bulb 11 is a pair of cold electrodes between which the arc is established. In order to render the lamp self starting, at least one of these electrodes is associated with an ionizing element which is adapted to be heated so as to assist in ionizing the gas or vapor within the bulb and in 55

starting the arc. Referring now to Fig. 2, one of the electrodes comprises a grid or coil 27 carried by a supporting wire 26, said coil surrounding and being electrically connected to a heated 5 ionizing element which in the form shown comprises a tube 16, preferably closed at one end, supported in the inner bulb 11 in any suitable manner as by means of a supporting band 17 and a supporting wire 18 that is fused in the stem 15. 10 The tube 16 may be of metal such as nickel or tungsten, or of conductive oxides such as zirconium oxide, etc. Preferably the tube is coated either partially or entirely with one or more oxides which have relatively high electronic emission 15 when heated, such as oxides of barium, strontium, thorium, etc., this coating being indicated diagrammatically at 19. Where the tube 16 is made of zirconium oxide and the like, one or more of these active oxides may be mixed with 20 the zirconium oxide.

The other electrode is constituted by a substantially cylindrical element 20 surrounding the electrode 27 and supported in any suitable manner as by means of wires 21 and 22 that are fused in 25 the standard 15. In the form shown, said element 20 comprises a wire screen, but it may be a cylindrical plate or coil.

A potential difference is established between the electrodes 27 and 20 in any suitable manner, 30 preferably by connecting in parallel with said electrodes a circuit which includes means for heating the ionizing element 16. As shown, one end of the filament 6 is connected to the wire 8, and the aforesaid parallel circuit is connected 35 between the wire 8 and the conductor 5. To this end a wire 23 is connected to the supporting wire 3 and also to the support 21. A resistance 24 is connected at one end to the electrode support 21 and at the other end to a heating filament 25 40 enclosed within the ionizing element 16. The other end of filament 25 is connected both to the tube support 18 and to the supporting wire 26 which carries coil electrode 27 surrounding the tube 16. Filament 25 may be insulated from the 45 tube 16 in any suitable manner as by coating said filament with a suitable cement.

When current is supplied to the lamp, it first flows in series through the conductor 4, supporting wire 7, filament 6, supporting wire 8, wire 23, 50 resistance 24, filament 25, wire 26 and conductor 5. It will be noted that the electrodes 20 and 27 are connected across or in parallel with the resistance 24 and the filament 25 so that the potential drop therethrough is impressed across said 55 electrodes to establish and maintain the arc therebetween. The arc may strike at once between the electrodes 20 and 27, in which case the tube 16 will practically remain unheated because the resistance 25, 24 is greater than the resistance 60 of the parallel arc path. If the arc fails to strike, the filament 25 heats the tube 16 and also supplies heat to the atmosphere of gas or vapor within the bulb 11. The heating of tube 16 drives off any ions of gas or vapor which were 65 adsorbed by said tube and also heats the oxide coating 19 so that the electronic emission therefrom assists in ionizing the arc atmosphere. As soon as the necessary degree of ionization is reached, the arc strikes and maintains itself between the grid or coil electrode 27 and the screen 70 electrode 20. As soon as the arc strikes, the resistance of the arc path is decreased and most of the current flows through the arc, the resistance 24 and filament 25 therefore tending to cool off. 75 The oxide coating 19 is protected against too

rapid disintegration by this cooling off of the filament 25 and also by the protection against electronic bombardment afforded by the grid electrode 27.

The electrode 27 should be negative with respect to the electrode 20 in order for the arc to operate properly in case direct current is used. This can be insured by proper wiring of the sockets in which the lamp is used, or if desired, a reversing switch of any suitable type may be included in the wiring connections to the socket so that if the arc does not start the polarities of the socket terminals may be reversed. Referring to Figure 1, a suitable socket is shown at 28, current being supplied to the socket by wires 29 and 15 30 which lead to the poles 31 and 32 of a reversing switch 33 of any suitable type. In case the lamp does not start when the switch 33 is closed, said switch is reversed in order to reverse the polarity of the electrodes 27 and 20. It will be 20 understood that the reversing switch is illustrated in diagrammatic form only; for example, it may comprise either a rotary switch or a knife switch and may have any suitable structural relationship with the socket 28.

It will be understood that the invention is not limited to the form described and illustrated in the drawing. Thus the bulb 1 may have any desired shape and size and may be mounted in any desired type of base. Similarly the bulb 11 30 may have any desired size and shape and may be supported within the lamp in any suitable manner. The ionizing element 16 may be of different materials as described above and may be of other forms than tubular. The grid electrodes 27 may also comprise a screen or the like instead of a coil. The electrical connections within the lamp may also be varied. For example, the resistance 24 may be constituted by a portion of the filament 6 by suitable connections 40 which will be apparent to those skilled in the art, and in some cases the resistances of the filament 25 will be sufficient without the use of additional resistances such as resistance 24. Other changes 45 may be made in the form, details of construction and arrangement of the parts without departing from the spirit of the invention and reference is therefore to be had to the appended claims for a definition of the limits of the invention.

What is claimed is:

1. An electric arc lamp comprising three concentric tubular elements, the inner element comprising an oxide coated member having high electronic emission when heated and the intermediate and outer elements comprising cold electrodes, a connection between the inner and intermediate elements placing said elements at substantially the same potential with respect to the circuit of the lamp, a single pair of lamp terminals, connections from said terminals to the intermediate and outer elements, and resistance means connected between said terminals and including a heating filament within said inner element and in parallel with said intermediate and outer elements.

2. An electric arc lamp comprising a tubular ionizing element coated with an oxide having high electronic emission when heated, a single pair of lamp terminals, a heating filament connected between said terminals and disposed within said ionizing element, a cold electrode adjacent said ionizing element and connected therewith, a second cold electrode spaced from said first electrode and ionizing element, and connections from said electrodes to said terminals.

3. An electric lamp comprising a bulb, an incandescent filament therein, an inner bulb, a tubular ionizing element coated with an electron emissive material disposed within said inner bulb, a cold electrode associated with said ionizing element, a second cold electrode in said inner bulb spaced from said first electrode, resistance means including a heating filament and connected in series with said incandescent filament across the terminals of the lamp, said heating filament being disposed within said tubular ionizing element, and connections from said electrodes to said series circuit at points of different potential.
4. An electric arc lamp comprising a bulb, a pair of cold electrodes in said bulb, a single pair of terminals for said lamp, connections between said terminals and said electrodes, an electron-emissive ionizing element in said bulb, and resistance means including a heating filament for said ionizing element connected between said electrodes in parallel with the arc path therebetween.
5. An electric lamp comprising a bulb, a pair of concentric cold electrodes in said bulb, a single pair of terminals for said lamp, connections between said terminals and said electrodes, an electron-emissive ionizing element adjacent to and electrically connected with one of said electrodes, and resistance means including a heating filament for said ionizing element connected between said electrodes in parallel with the arc path therebetween.
6. An electric lamp comprising an outer bulb, an incandescent filament in said outer bulb, an inner bulb, a pair of cold electrodes in said inner bulb, a single pair of terminals for said lamp, said incandescent filament and electrodes being connected in series across said terminals, an electron-emissive ionizing element in said inner bulb, and resistance means including a heating filament for said ionizing element connected between said electrodes in parallel with the arc path therebetween.

GEORGE SPERTI.
